LATTICE GIRDER
Helmut Pötzsch, Mainz (Rhine), Germany, assignor to
Fritz Grebner, Mainz, Germany
Continuation of application Ser. No. 584,921, May 15,
1956. This application Sept. 27, 1960, Ser. No. 58,822
Claims priority, application Germany May 18, 1955
2 Claims. (Cl. 189—37)

The present invention relates to lattice girders and structural frameworks suitable as supports for reinforced concrete ceilings and the like.

It is a principal object of this invention to provide a novel lattice girder and framework which may be mechanically mass-produced from simple, commercially available wire and rod materials and which is rigid in at least two supporting planes, such girders serving to construct self-supporting steel frameworks which are static and rigid in at least two dimensions. If desired, the girders of the invention can be made rigid in three dimensions with the same mechanical mass production methods. A structural support framework of this type is capable of carrying loads required in ceiling supports, for instance.

It is another object of the invention to provide a lattice girder of this type, which also includes reinforcing armor for the lateral portions of the concrete footing which carries the hollow ceiling blocks of a ceiling structure.

The above and other objects and advantages are accomplished in accordance with the invention with a three-dimensional lattice girder which comprises an upper boom consisting of a longitudinal rod, a lower boom consisting of two longitudinal rods and a plurality of substantially V-shaped rods constituting crossties arranged in diagonal planes between the upper and lower booms transversely thereof. The apexes of all crossties are spot-welded to the upper side of the longitudinal rod constituting the upper boom, the apexes of adjacent crossties whose planes are inclined toward each other being slightly spaced from each other, and the two ends of each cross-tie are spot-welded to the upper side of respective ones of the longitudinal rods constituting the lower boom, the ends of adjacent ones of the crossties whose planes diverge being slightly spaced from each other. The ends of the crossties are bent to extend horizontally outwardly from the lower boom, thus forming a reinforcing armor for the lateral portions of a concrete ceiling support footing in which the lower boom of the girder may be embedded. By slightly spacing the apexes and ends of adjacent crossties, the girder may readily be cut to any desired length between adjacent crossties without weakening the girder at that point. Since only two girder elements are arranged one above the other at any point of spot-welding, the girder may be readily mass-produced by longitudinally feeding the elements to the spot-welding station.

It is possible to form from a plurality of three-dimensional lattice girders situated side by side parallel to one another, a structural steel lattice framework in which the individual girders are connected together by the outwardly extending ends of the diagonal crossties extending at right angles to the longitudinal axis of the girders. With this arrangement, the lattice framework is composed of rigid girders arranged parallel to and adjacent one another, which may also be used as individual girders by being cut up. In this way, the novel structural steel lattice framework is much more adaptable than hitherto known lattice works, without requiring any greater outlay in material or manufacture.

Such lattice girders and structural steel lattice frame-

2

works may be made either by feeding all the rods or bars in one plane through a spot-welding machine while the previously bent crossties are fed in and fixed in stages and, finally, the longitudinal rods situated in the middle of each individual girder are bent out from the plane together with the corresponding parts of the crossties, thus forming the desired three-dimensional structure, or the feed may be carried out from the beginning in two planes, so that only the pre-bent crossties have to be fed in or fixed. In the first case, in which all the longitudinal bars are fed in one plane, the bars which are situated centrally of a girder being formed and which will later be lifted out of the plane of the girder, are located at a larger distance from the neighboring transverse bars, this distance being reduced when the three-dimensional structure is produced.

The above and other features of the invention will be more fully set forth in the detailed description of certain now preferred embodiments thereof, taken in conjunction with the accompanying drawing wherein:

FIG. 1 is a plan view of a girder according to the invention;

FIG. 2 is a side view of the girder according to FIG. 1;

FIG. 3 is a perspective view of the girder according to FIG. 1;

FIG. 4 is a transverse cross section showing the girder embedded in a ceiling support footing of a ceiling structure;

FIG. 5 is a plan view of part of a structural steel lattice framework, according to the invention;

FIG. 6 is a perspective view of the structural steel lattice framework.

The girder shown in FIGS. 1 to 4 consists of the two lower boom rods 1 and the upper boom rod 2, which are straight and arranged longitudinally. The booms are connected together by V-shaped crossties 3 which extend in the transverse direction from one lower boom rod over the upper boom to the lower boom rod and are so inclined relatively to one another that the two planes which are formed at an angle to one another by the diagonals are statically stable, capable of carrying loads and symmetrical. Of course, it is also possible to obtain asymmetrical support planes by suitable arrangement of the diagonals. The drawing shows that, at all points of intersection, only two elements lie one above the other and the diagonals bear against one side only of all the boom rods. In this way, using previously bent crossties, the girders can in practice be produced continuously and by mechanical means in one operation.

If desired, transverse rods 4 may also be provided and are spot-welded to the boom rods 1 between each pair of crossties or between each group of more than two crossties. These transverse rods render the girder load-supporting in three dimensions. As shown, the transverse elements 3 and 4 are spaced from each other at the points where they are spot-welded to the longitudinal boom rods so that the girder may be cut at any desired point between adjacent transverse elements.

As shown in FIG. 4, when the girder of FIGS. 1-3 is embedded in a concrete footing 5 forming part of a ceiling support, the outwardly extending straight ends 3' of the crossties 3 form a reinforcing armor for the lateral portions of the concrete footing which support the hollow ceiling blocks 6.

As is known, the lateral load-carrying portions of the concrete support are subject to cracking and the reinforcement supplied by the crosstie ends is, therefore, of considerable practical advantage.

The lattice framework illustrated in FIGS. 5 and 6 is composed of the longitudinal rods 1 and 2 and the pre-bent continuous crossties 3a. In the illustrated embodiment, the arrangement is such that each two longitudinal

3

rods 1 are situated parallel and adjacent one another in a lower plane, while between each pair of said rods 1 a further longitudinal rod 2 is situated in a plane thereabove. The lower rods form the lower boom of individual girders, while the intermediate upper longitudinal rods form the upper boom of girders which are connected together by the continuous transverse crossties 3a.

In the manufacture of the girders or lattice framework, the crossties are fed and spot-welded to the longitudinal rods in such manner that they always bear all 10 against the upper side of the longitudinal booms, as illustrated, in such a way that no more than two rods lie one on top of the other. The diagonals 3 or 3a are previously bent so that in the main parts of the girder or structural steel lattice framework, triangular meshes are formed so that the two planes of the individual girders which are disposed at an angle relatively to one another constitute rigid, statically determinate and symmetrical planes; asymmetrical support planes can also be formed by suitable pre-bending of the diagonals.

The novel structural steel lattice framework is so constructed that it can be cut up into one or more girders at any time, and the individual parts can be used by themselves for any structural elements, more particularly as ceiling support elements. In the illustrated embodiment it is advantageous to execute the cuts through the transverse connecting pieces in such a way that the girder is formed with two longitudinal rods as a lower boom and one longitudinal rod as an upper boom.

While the invention has been illustrated and described in connection with certain preferred embodiments, it will be clearly understood that many variations and modifications may occur to the skilled in the art after benefiting from the present teaching without departing from the spirit and scope of the invention as defined in the appended claims.

This is a continuation of my application Serial No. 584,921, filed May 15, 1956, now abandoned.

What I claim is:

1. A three-dimensional lattice girder comprising an upper and a lower boom, the upper boom consisting of one longitudinal rod and the lower boom consisting of two longitudinal rods, and a plurality of substantially V-shaped rods constituting crossties each having an apex and two ends which project horizontally outwardly from the lower boom rods, the crossties being arranged in diagonal planes between the upper and lower booms transversely thereof, the apexes of all crossties being spot-welded to the upper side of the longitudinal rod consti- 40

tuting the upper boom and the apexes of adjacent ones of said crossties whose planes are inclined toward each other being slightly spaced from each other, and the two ends of every one of said crossties being spot-welded to the upper side of respective ones of the longitudinal rods constituting the lower boom and the ends of adjacent ones of said crossties whose planes diverge being slightly spaced from each other, and only two girder elements including the rods and crossties being arranged one above the other at the point of spot-welding.

2. A structural framework comprising a plurality of adjacent lattice girders, each girder including an upper and lower boom, each upper boom consisting of one longitudinal rod and each lower boom consisting of two longitudinal rods, the rods being parallel to each other and all the upper booms lying in one plane while all the lower booms lie in a plane spaced therefrom, and a plurality of transverse rods constituting crossties each consisting of a plurality of substantially V-shaped portions integrally interconnected by straight end portions, each V-shaped portion having an apex, the crossties being arranged in diagonal planes between the upper and lower booms transversely thereof, the apexes of all crossties being spot-welded to the upper sides of the longitudinal rods constituting the upper booms and the apexes 15 of adjacent ones of said crossties whose planes are inclined toward each other being slightly spaced apart from each other, and the straight end portions of every one of said crossties being spot-welded to the upper sides of respective ones of the longitudinal rods constituting adjacent ones of said lower booms and the straight end portions of adjacent ones of said crossties whose planes diverge being slightly spaced from each other, and only two girder elements including the rods and crossties 20 being arranged one above the other at the point of spot-welding.
